UNITED STATES PATENT OFFICE.

MOSES K. BORTREE, OF JACKSON, MICHIGAN.

CORSET.

SPECIFICATION forming part of Letters Patent No. 239,295, dated March 22, 1881.

Application filed November 29, 1880. (No model.)

To all whom it may concern:

Be it known that I, MOSES K. BORTREE, of the city and county of Jackson, Michigan, have invented an Improvement in Corsets, of which the following is a specification.

The nature of this invention relates to certain new and useful improvements in the construction of corsets, and is designed as an improvement upon Letters Patent granted to me

July 27, 1880, No. 230,462.

The object of this invention is to provide a vertically-adjustable bust for corsets that may be detached from either side for the purposes of nursing without the necessity of entirely re-
moving the bust-piece from the body of the corset.

The invention consists in the peculiar construction and arrangement of the parts, all as more fully hereinafter set forth.

Figure 1 is a perspective of a corset provided with my improved adjustable bust. Fig. 2 is a perspective, from the inside, of one of the busts removed.

In the accompanying drawings, which form a part of this specification, A represents one-half of a corset-body, the upper front portion of which is cut away, as shown at a, and the vertical sides of this cut-away portion are provided with the hooks b.

B represents the bust-section formed into the proper shape, and in the two sides thereof is secured the series of eyelets c, which, when the bust is in place, engage with the hooks b, as may be desired. The bust-section B is made smaller at its lower end, as shown at h, Fig. 2, to fit into the pocket i in the corset, in which it may be vertically adjusted.

By this construction and arrangement of parts the bust can readily be adjusted as the wearer may desire, and one side of the bust can be detached and folded back for nursing without changing its vertical adjustment.

If desired, the bust-pieces may be provided with flaps d', to conceal the hooks and eyelets, and to prevent their catching in the outer garments.

What I claim as my invention is—

1. In combination with a corset provided with a vertical adjustable bust, the hooks and eyes, or equivalent fastening, by means of which one side of said bust may be detached and adapted to be folded back without changing its vertical adjustment, substantially as described, and for the purpose set forth.

2. The combination, with the half-corset A, cut away at a, and provided with the pocket i and hooks b, of the bust-section B, having its smaller end h shaped to fit into said pocket, and provided with the eyelets c, substantially as described, and for the purpose set forth.

3. The combination, with the half-corset A, cut away at a, and provided with the pocket i and hooks b, of the bust-section B, having its smaller end h shaped to fit into said pocket, and provided with the eyelets c and flaps d', substantially as described, and for the purpose set forth.

MOSES K. BORTREE.
